UNITED STATES PATENT OFFICE.

WILLIAM A. LACKE, OF CHICAGO, ILLINOIS.

THERMOSTAT.

Application filed May 6, 1920. Serial No. 379,255.

To all whom it may concern:

Be it known that I, WILLIAM A. LACKE, a citizen of the United States, residing at Chicago, in the county of Cook and State of Illinois, have invented a certain new and useful Improvement in Thermostats, of which the following is a specification.

This invention relates to thermostatic mechanism for use in temperature regulation of various sorts of apparatus. It is especially adapted for use in connection with the regulation of steam radiators and boilers, hot air furnaces and other devices used in heating buildings.

15 The objects of the invention are to provide a clock controlled mechanism adapted to, at predetermined times, shift the temperature of regulation for the heat in a given room or apparatus from one predetermined temperature to another, as for instance, from one temperature for day to another by night; this in combination with mechanism by which the operator may at will selectively vary either the day or night temperature, or both and this further in combination with means for readily calibrating the instrument so that a readable scale will plainly indicate to the operator the range of temperatures through which the device operates.

20 The invention consists in means for carrying out the foregoing objects which can be easily and cheaply made, which is very satisfactory in operation and is not readily liable to get out of order. More particularly 25 the invention consists in many features and details of construction more fully set forth in the specification and claims.

Referring to the drawings in which similar numerals represent the same parts throughout the several views,

Figure 1 is a face view of a thermostat constructed to illustrate this invention in its preferred form,

Figure 2 is a side view partly in section taken on the line 2—2 of Figure 1.

Figure 3 is a sectional plan view taken on the line 3—3 of Figure 1.

Figure 4 is a face view showing in detail certain parts, the same taken on the irregular line 4—4, Figure 2.

Figure 5 is an inverted plan view on the line 5—5, Figure 3.

The entire mechanism is carried as a unit on a suitable base member 16, in the particular case here illustrated, carried by the enclosing flanges 18 whose edges 20 bear on the

wall or other surface to which the device is attached.

On plate 16 near its bottom is a bracket 22 to which is attached and about which is coiled the usual thermostatic element 24 whose free vibrating arm 25 which serves as one example of a thermostatically urged member, extends up the plate 16 along approximately its center and by lateral movement parallel to the face of the plate 16 indicates or measures changes in thermostatic conditions of the room in which the device is located.

Pivoted to base 16 at approximately the pivotal center about which the thermostatic arm 25 swings, in the particular case here illustrated, on the screw or stud 26, is a vertically extending carrier member, in the particular case here illustrated, a lever, or 70 pendulum 28 adapted to swing laterally across plate 16 in a plane between the arm and plate. Secured to the pendulum 28 by any suitable means is a downwardly open U-shaped insulating block 30 having its arms 80 embracing opposite sides of the thermostatic arm 25 to support the adjustable electric contact screws 32 and 34 adapted to be selectively engaged by the thermostatic arm 25 as it swings backward and forward in 85 the usual manner to indicate differences in temperature. These terminals 32 and 34 are connected by wires 35 and 36 to terminals 37 and 38 conveniently located at the bottom of the plate 16 and the thermostatic element 24—25 is connected by wire 39 to the terminal 40 located between terminals 37 and 38. These terminals 37, 38 and 40 are connected by wires (not shown) to the apparatus to be controlled by the mechanism 90 of this invention in such manner that when thermostatic arm 25 engages contact 34 the heating apparatus is turned off and that when arm 25 swings to contact member 32 the heat is turned on, this all in the manner well understood in the art. In other words the arm 25 swings to the left as the temperature goes down from which it follows that the cooling off of the room and arm 25 will cause it to contact member 32 100 and turn on the heat when the pendulum is in the position shown at a much higher temperature than it will if the pendulum and arm 25 are forcibly swung over to the left, say until pendulum 28 contacts stop 103. In 105 this latter position the temperature will be much lower before arm 25 will be cool

enough to swing over against contact 32 and turn on the heat.

Pendulum 28 is provided at some point in its length, in the particular case here illustrated, at the extreme top of the plate 16 with a graduated scale device designed to indicate the temperature at which the heat is shut on and off. In the particular case here illustrated this indicating device comprises a plate 42 attached to the plate 16 thru the agency of pin 44 and elongated slot 46 connections, so arranged that the plate 42 may be moved a substantial distance transversely on the plate 16. The plate 42 is provided with a graduated scale 48 registering with an indicating pointer 50 on the pendulum 28, said pointer in the particular case here illustrated lying on one side of the circular perforation 52 thru which the observer looks at the scale graduations 48. In the use of this particular part of the mechanism the operator takes a suitable thermometer and with the pendulum in the position shown determines what the temperature is, and thereupon adjusts the scale plate 42 so that the graduations of the scale 48 correspond to the indicated temperature. Thereupon subsequent rocking of the pendulum 28 about pivot 26 will cause the pointer 50 to register with graduations on the scale 48 one side or the other of the initial graduation corresponding to the actual temperature in the room;—it being of course understood that the scale 48 was originally made to indicate correctly these variations in temperature. The scale may be made originally or calibrated by making such a test for each desired temperature and marking the positions of pointer 50 on scale 48.

Supported a substantial distance in front of plate 16, is a clock mechanism 54. In the particular case here illustrated this is attached to the plate by a hinge mechanism 56 on one side and a catch mechanism 58 on the other side, both without special novelty and therefore not shown in detail. When the catch mechanism 58 is released the clock may in the manner hereafter described be swung on the hinge 58 to obtain ready access to the back of the clock for winding, etc. as hereafter set forth. It is evident that this clock could also be reversed and the hinge be dispensed with in which case the clock would simply be supported in a non-pivotal position upside down on the plate 16, the winding and setting mechanism then being in proper position for manipulation and the arm 28 then passing over the top of the clock instead of under. In the particular case here illustrated this clock 54 is an ordinary clock having the usual time indicating front dial 60 and hands 62, and having on its rear a shaft 64 driven by the clock to rotate in unison with the hour hand one

revolution per hour. The usual handle or thumb nut 66 for manually operating this shaft is shown in the drawing, but does not enter into the invention. Rigidly mounted upon the rear of the clock case, in the particular case here illustrated at a point near its bottom, is a stud 68 on which is journaled the hub 70 of a gear 72. Between gear 72 and shaft 64, heretofore described, is a suitably arranged train of gearing 74 so proportioned that gear 72 makes one complete revolution in 24 hours, as indicated by the clock.

Telescoping with the stud 68 and the hub 70 is a hub 76 carrying a dial plate 78 on whose face is placed as shown in Figure 4, graduations 80 indicating the 24 hours of the day. In the particular case here illustrated these graduations take the form used in this country of two sets of numerals 85 reading from 1 to 12, one set indicating the time from noon to midnight and the other set the time from midnight to noon.

Hub 76 is, as shown in Figure 3, made substantially larger than hub 70, and is made with an angularly inclined central bore in which and against which the hub 82 of a cam 84 is adapted to fit and be pressed into frictional engagement thru the agency of a washer 86, a spring 88, and an adjusting nut 90. The clock therefore propels and consequently regulates cam 84—84^a. In actual practice these parts are so arranged that the cam 84 is held sufficiently tightly pressed against the hub of the disk 78 so that for practical purposes of operation of the device they are rigid with reference to each other but that the operator may by manually taking hold of the two parts adjust them angularly with reference to each other under the control of spring 88.

The cam 84 is made in two parts 84 and 84^a adapted to be angularly adjusted with reference to each other, for the purposes hereafter described, in the same manner that the cam is adjusted with reference to disk 78. The two cam parts 84 and 84^a are normally held for practical purposes rigid with each other by the action of spring 88.

The cam 84 has a circular surface 92 and an inwardly cut surface 94. The object of having a cam made in two parts and adjusting them angularly with reference to each other, is to increase or decrease the circumferential length of the usually but not necessarily high temperature surface 92 so as to extend it at the will of the operator over a greater or less number of hours indicated on the disk 78—this to take care of variations in the length of time during the day or night in which a given temperature is to be provided. In the particular case here illustrated, as shown in Figure 4, the complete cam 84 is arranged so that the temperature controlled by surface 92 is in effect from

six in the morning until 9 at night, and the temperature controlled by or thru the presence of surfaces 94 extends from 9 p. m. to 6 a. m. By shifting cam members 84 and 84^a angularly of each other the cam may be made, for instance to take care of the time from 7 a. m. to 8 p. m. By shifting the entire cam with reference to the disk 78 under the control of spring 88 the cam as shown may be made to take care of the temperature from 7 a. m. to 10 p. m. or from 4 a. m. to 8 p. m. etc.

Pivoted to the pendulum 28 at a convenient point adjacent to but remote from the cam is a lever arm 96. In the particular case here illustrated this pivoting is effected by screw 98 passing thru the arm and entering the pendulum and so arranged that by tightening the screw the swinging arm 96 may be rigidly held in position or held in such a position that it is for working purposes rigid, but may be manually moved by the operator angularly about the screw 98. The lower end of the arm 96 is provided with a handle 99 for convenient manipulation of the lever, as just described. This lever 96 carries at its lower end a suitable roller 100 designed to travel upon the circular surface 92 of cam 84. This lever 96 is nothing in the world but a convenient means of shifting the distance between roller 100 and the central axis of the pendulum.

The pendulum 28 and consequently arm 96 are normally drawn to the left as viewed in Figure 1 by a retractile spring 102 with the result that this roller 100 is positively held upon the surface 92 of cam 84.

Plate 16 is provided at a convenient point, in the particular case here illustrated near its middle, with an elongated horizontal slot 104 in which is detachably secured a sliding stop 106. In the particular case here illustrated this stop takes the form of a screw having a thumb nut head 108 which may be so tightened up to fasten the screw in any desired position in this slot 104. This stop mechanism is adapted to be engaged by the left hand side of the pendulum 28 and is adjusted by the operator so that when the pendulum is in contact with it the pointer 50 will indicate the temperature which it is desired the heating apparatus shall provide during the night, or other period of the day in which the roller 100 is not controlled by the surface 92 of the cam but is in proximity to the cam surfaces 94.

In the operation of the device the operator takes hold of handle 93^a and moves arm 96 to such a position that roller 99 travels on circular face 92 of the cam at the temperature indicated on scale 48 which he desires to be in effect during the day or some other selected portion of the 24 hours of the day, using for the purpose of determining the temperature the previously calibrated and

adjusted scale 48. He then adjusts the stop 106 so that the pendulum 28 will just strike it when the thermostatic element 25 engages contact 32 at the temperature desired for the night. By this adjustment the operator establishes the selectively variable temperature at which the device is to operate when cam face 92 is engaged by roller 100. He then takes hold of the cam 84 and adjusts it angularly with reference to the disk 78 and adjusts the parts of the cam 84 with reference to each other, so that the maximum temperature will be maintained during the hours he wishes it and the minimum temperature be correspondingly maintained. Thereupon the device is ready for use for as many days, weeks or months as the operator has no desire to change his hours and temperature. When changes are desired they may be made in the manner indicated. When the machine is so adjusted the clock runs in the ordinary manner. During the hours, usually the day, when maximum temperature is desired, the roller 100 travels on cam surface 92, with contact 32 in engagement with arm 25. As soon as the clock rotates cam 84 far enough so that roller 100 can travel on face 94, spring 102 draws the pendulum over against stop 106, thus forcing arm 25 into engagement with contact 34, thus shutting off the heat, which condition exists until the clock moves cam 84 far enough to restore roller 100 to cam surface 90, thereby throwing contact 30 into engagement with arm 25 and restoring the heat.

Attention is called to the fact that when it is necessary to wind the clock it is only necessary for the operator to release catch 58, swing the arm 96 so that the roller 100 clears the cam 84, whereupon the clock mechanism will be swung outward from the hinge mechanism 53. This swinging action may be taken advantage of when the operator desires to adjust the cam with reference to the disk, heretofore described. These adjustments may, however, be made from below the clock without moving it from normal position.

Also this clock can be mounted upside down on the base member 16 so that the clock would not need to be pivoted.

Having thus described my invention what I claim as new and desire to secure by Letters Patent, is —

1. A thermostat including a thermally movable arm, a member adjustable to different normal operative positions with respect to said arm and having two movements in all said positions, contacts carried by said member and engageable by said arm, clock controlled mechanism for effecting said movements when the member is in any normal position, said mechanism including a cam operable to effect one of said movements, and means to maintain the movements of the member in-

parted by said cam equal in extent in all normal positions of the member.

2. A thermostat including a thermally removable arm, a member adjustable with respect to said arm, contacts carried by said member engageable by said arm, a clock controlled cam operable to maintain said member and the contacts carried thereby in a predetermined operative relation with respect to said arm over a predetermined period of time, and an adjustable connection between said cam and member whereby the same operative relation aforementioned between the arm and member may be maintained in different adjusted positions of the member with respect to the arm.
3. A thermostat including a thermally removable arm, a member adjustable with respect to said arm, contacts carried by said member engageable by said arm, a cam engageable element carried by said member, and a clock controlled cam engaging said element thereby to maintain the member and the contacts carried thereby in a predetermined operative relation with respect to said arm over a predetermined period of time, said cam engaging element being adjustable toward and away from said member whereby the same operative relation aforementioned between the arm and member may

be maintained in different adjusted positions of the member with respect to the arm.

4. A thermostat including a thermally removable arm, a member adjustable with respect to said arm, contacts carried by said member engageable by said arm, a cam engageable element carried by said member, and a clock controlled cam engaging said element thereby to maintain the member and the contacts carried thereby in a predetermined operative relation with respect to said arm over a predetermined period of time, said cam engaging element including a lever pivoted to said member and adapted to be angularly adjusted with respect to said member thereby to dispose its cam engaging portion a greater or less distance from the member, whereby the same operative relation aforementioned between the arm and member may be maintained in different adjusted positions of the member with respect to the arm.

In witness whereof, I have hereunto subscribed my name in the presence of two witnesses.

WILLIAM A. LACKE.
